UNITED STATES PATENT OFFICE

CHRISTIAN J. FUSE, OF BROOKLYN, NEW YORK, ASSIGNOR TO AMERICAN MACHINE & FOUNDRY COMPANY, A CORPORATION OF NEW JERSEY

CIGARETTE-MACHINE FEED

Application filed April 4, 1928. Serial No. 267,460.

This invention relates to a cigarette machine tobacco feed, its main object being to provide an improved machine of this type which is compact, which will feed the tobacco uniformly, and which is adaptable to properly feed tobaccos differing considerably in condition and variety.

Hitherto the feed drum and the means for regulating the amount of tobacco fed by the feed drum, have been driven from a common drive-shaft by belts or chains, resulting in slippage in the case of the belts and back-lash in the case of the chain drive. It has been found that this slippage or back-lash results in uneven feeding of the tobacco, due to lack of uniformity between the driving of the feed drum and the regulating means, and it is an object of the invention to remedy this defect.

In previous machines of this type, the picker rolls have been driven from the same shaft as the feed drum and other feed regulating mechanism of the machine. It has been found desirable to vary the relative speed of the picker rolls and the feed drum in order to obtain more uniform results with tobaccos varying in condition or variety. It has also been found that varying the speed of the picker roll with respect to the feed drum makes it possible to change the density of the tobacco in the cigarette rod, and thus obtain a cigarette having the proper "feel". By "feel" is meant the resistance to pressure resulting from the density of the tobacco confined in the rod. It is, therefore, an object of this invention to provide an independent drive for the picker rolls, by which the speed of the picker rolls may be adjusted with respect to that of the feed drum and feed regulating mechanism of the machine.

Hitherto it has been found necessary to provide a winnowing device extending a considerable distance in front of the feeding machine, receiving the tobacco thrown from the side of the feed drum. It has been discovered that a much more compact machine may be produced without sacrificing efficiency by rebounding the tobacco thrown from the feed drum on a wall close to said

drum, to deliver the winnowed tobacco underneath the drum. It is another object of the invention to produce a more compact machine than heretofore known embodying this discovery.

In the accompanying drawings:

Fig. 1 is an elevation of one side of the tobacco hopper, showing the main drive;

Fig. 2 is an elevation of the opposite side of the tobacco hopper, showing the drives for the winnowing, fan and conveyor screw;

Fig. 3 is a front elevation of the tobacco feed;

Fig. 4 is a sectional side elevation of the tobacco feed taken on line 4-4 of Fig. 3, and showing the manner of feeding the tobacco; and

Fig. 5 is a partial side elevation of the lower part of the tobacco feed modified for single picking, the parts shown in Fig. 4 for the re-picking of the tobacco being omitted.

In carrying the invention into effect, there is provided a feed drum for forwarding tobacco from a mass in a hopper or other suitable receptacle, and means are provided for regulating the amount of tobacco forwarded by said drum, together with worm gearing driving said drum and said regulating means. There is further provided picking mechanism acting on the tobacco forwarded by said drum, and means independent of said gearing for driving said mechanism. In the best constructions also, there is provided a winnowing device operating to deliver winnowed tobacco underneath the drum. In the best constructions contemplated, this winnowing device consists of a wall and means for throwing tobacco against the wall to cause its lighter parts to slide down the wall and to cause its heavier parts to rebound from the wall and thereby become separated from the lighter parts. The best constructions also include a re-picker acting on the tobacco after it is winnowed.

The means above referred to may be widely varied in construction within the scope of the claims, for the particular machine selected to illustrate the invention is but one

of many possible embodiments of the same. The invention, therefore, is not to be restricted to the precise details of structure shown and described.

Referring to the drawings, the tobacco feed consists of a hopper 10 which is held together by locks 11 and has an inclined top-cover 12 attached to the side walls by hinges 13, and which contains the various feeding and picker devices for disentangling the shredded tobacco used for making cigarettes. These devices include a belt 14 which presses the mass of tobacco against a feed drum 15, a regulating drum 16 which sweeps the excess tobacco off the feed drum, these elements together constituting the means for regulating the amount of tobacco forwarded by the feed drum, a fan 17 which blows out the dust and brushes off clinging shreds of tobacco on the regulating drum, a comb 18 which compacts the tobacco left by the regulating drum 16 on the feed drum 15, a picker roll 19 which picks off and throws the tobacco from the feed drum 15 against a glass wall 20, a trough 21 which catches the heavy parts of the tobacco rebounding from the wall 20, and a re-picker comprising re-picker drum 22 and re-picker roll 23, which re-pick the tobacco before its delivery to the cigarette machine.

The hopper 10 is mounted between the end-frames 24 and 25, which are held together by the rods 26, and are supported by the pedestals 27. The frames 24 and 25 support a shaft 28, which carries a belt-pulley 29 carrying the pressure belt 14, which also runs over a pulley 30 on shaft 31 located in suitable bearings in the hopper. This belt serves to press the tobacco in the hopper against the feed drum.

A shaft 28, within a housing 32 which is attached to a lower worm-housing 33 carried by the end frame 24, has a worm wheel 34 in mesh with a worm 35 on a drive shaft 36, which is supported in worm-housing 33 and in a sleeve 37 attached to a frame 24. The sleeve 37 terminates in an upper worm-housing 38, to which is fastened a worm wheel-housing 39. The lower overhanging part of frame 24, together with housing 33, carries a shaft 40 having a worm 41 in engagement with a worm wheel 42 on the inclined drive-shaft 36, and thereby drives the shaft 36 from the shaft 40, which is in turn driven by the motor-driven chain 43 running over sprocket 44 on the shaft 40. The drum 15 is mounted on a shaft 45, located in bearings in the frames 24 and 25, and driven from the shaft 36 by the worm 46 in the housing 47. The overhanging end of the shaft 45 is provided with a worm wheel 48 in a housing 49 attached to the sleeve 37, this wheel being in mesh with the worm 46, thereby driving the shaft 45.

It will be noted that the feed drum, the

regulator drum and the pressure belt are directly driven by worm gearing from a single drive shaft. Thus there will be no slippage and substantially no back-lash in the drive, and a uniform driving relation will be maintained between these parts at all times.

The tobacco is pressed against the rotating feed drum 15 by the belt 14 and is picked up by the same, the overhanging shreds being swept off by the pins of regulating drum 16, when the feed drum has turned into engagement with them. The regulating drum 16 is mounted on a shaft 50, which is supported in adjustably mounted bearings 51 and 52, the former being attached to the frame 24, and the latter to the frame 25. The shaft 50 is driven by a worm 53 on the shaft 36, the worm being located in the housing 38 and in mesh with a worm wheel 54 in the housing 39, the worm wheel 54 being mounted on the shaft 50.

Tobacco shreds protruding from the drum 16 are removed by the fan 17, which is affixed to a shaft 55 held in eccentrically mounted bushings 56 located in the end frames 24 and 25. By loosening set-screws 57, the bushings 56 can be turned, thereby adjusting the distance of the fan from the drum 16. The fan is operated by a pulley 58 on the shaft 55, connected with a pulley 59 on the shaft 60 by a belt 61. Shaft 60, which carries the picker roll 19 and a picker roll pulley 62, is located in adjustable bearings 63 and 64 on the frames 24 and 25, and is driven by a motor 65 fastened to the under side of the frame 25, its step-pulley 66 being connected with a step-pulley 67 on shaft 60 by means of a belt 68. The driving means for the picker roll 19 and re-picker roll 23 is, therefore, entirely independent of the worm drive for the feed drum and feed regulating means 14 and 16. Accordingly, the speed of the picker mechanism can be varied with respect to the feed and feed regulating mechanism by merely placing the belt 68 on different steps of the step-pulleys 66 and 67, or by varying the speed of the motor 65.

A drawer 69 placed in the hopper 10, underneath the drum 16, catches any tobacco remnants not fully cleaned away by the fan 17.

The tobacco remaining on the feed drum 15, after emerging from contact with the regulating drum 16, is pressed against the drum by the teeth of the comb 18, which project into the spaces between the pins of drum 15. Comb 18 is attached to shaft 70, which is supported by frames 24 and 25, and on which is mounted the lever 71 having the spring 72 for keeping the comb in tension.

Upon being taken from drum 15 by the pins of picker roll 19 on shaft 60, the to-

bacco is thrown against the glass plate 20 located close to the drum, which forms the lower front wall of the tobacco magazine, and which is held by the two adjustable angle-pieces 73. An adjustable wall 74, mounted close to picker roll 19, prevents the tobacco from being thrown in an upward direction. The heavy parts of the tobacco such as the stems and foreign matter re-
bounding from wall 20, are caught by the trough 21 spaced away from the wall, while the tobacco shreds slide down the wall and are delivered underneath the feed drum and on the top of the re-picker drum 22, which is set close to the lower end of the wall 20. The wall 20, as herein arranged, constitutes the winnowing device which, because it is close to the feed drum and delivers the winnowed tobacco underneath the drum, makes possible a very compact machine, in which no additional floor space is required on account of the winnowing device.

The trough 21, which is supported below and close to the drum between the bearings 25 74 on which it is rotatable so that its angular position can be adjusted to the trajectory of the heavy parts of the tobacco, terminates in a chute 75 protruding from the side of the hopper 10. The heavy parts 30 of the tobacco in the trough are propelled into the chute 75 by a conveyor screw 76, which is mounted in the bearings 74 and driven by a pulley 77 on the shaft 78 of the screw, this pulley being connected by a belt 35 79 with the pulley 80 on the shaft 45.

The tobacco dropping on the re-picker drum 22 is subjected to re-picking to break up the tobacco shreds and to provide the extra picking found desirable for certain 40 types of tobacco. The re-picker drum 22 and its associated re-picker roll 23 are supported by bearing brackets 81 and 82 attached to the under sides of the frames 24 and 25. The re-picker drum 22 is partly 45 surrounded by a concave guide 83 attached to the bearing brackets 81 and 82, while the re-picker roll 23 is provided with the guide wall 84 fastened to the same brackets, both guide elements serving to guide all 50 the descending winnowed tobacco into the re-picking device. The re-picker drum 22 is slowly driven by the shaft 45, the sprocket 85 on its shaft 86 being connected by a chain 87 with a sprocket 88 on the shaft 55 45. The shaft 89 of the re-picker roll 23, for the purpose of adjustment, is eccentrically mounted in the bushings 90, and is provided with a pulley 91 which is connected by a belt 92 with the swiftly rotat- 60 ing pulley 62 on the shaft 60.

A tobacco delivery chute 93, placed below the rolls 22 and 23, is clamped between screws 94, located in brackets 81 and 82. Secured to the shaft 86 is a starwheel 95, 65 which engages with a roller 96 of a lever

97 mounted on a shaft 98 supported in brackets 81 and 82. On the shaft 98 is mounted a lever 99, arranged in such a manner as to knock against the rear wall of chute 93 every time the roller 96 is lifted by starwheel 95, thereby setting the chute into vibration and preventing accumulation of tobacco in the same. A spring 100 pulls the roller 96 back into engaging position with starwheel 95, after it has been raised by one of the points of the latter.

On the side of the hopper 10, shown in Fig. 1, is mounted a frame 101 which, in threaded bushings 102 carries the threaded shafts 103 projecting into the magazine 10 and rotatably attached to the division wall 104 in said magazine. On the bushings 102 are mounted sprockets 105, which are connected by a chain 106 with a sprocket 107 on a shaft 108 having a handwheel 109. An idler 110 on an arm 111 serves to adjust the tightness of the chain 106. By turning the handwheel 109, the partition 104 can be moved forward and back, thereby adjusting the breadth of the tobacco stream issuing from the delivery chute 93 and thus controlling the amount of tobacco deposited upon the cigarette paper strip passing below it.

In cases where the second picking is not needed, the machine is modified as shown in Fig. 5. In this form the drum 22 and roll 23 are omitted, and the tobacco sliding down the glass wall 20 enters directly into chute 112 clamped between screws 113 in brackets 114, which also support a shaft 115 having secured to it the lever 116 and the knocker 117. Lever 116 has the roller 118 held in engaging position with starwheel 119 on shaft 45 by the spring 120.

The pressure belt 14 is supported by the bottom plate 121 and can be tightened by means of screws 122 located in frames 24 and 25, these screws carrying the blocks 123 which support the idler 124. Between belt 14 and drum 15, a guard-plate 125 is placed extending from frame 24 to frame 25, to protect the belt from damage by the pins of drum 15.

What is claimed is:

1. In a cigarette machine feed, the combination with a feed drum, of means for regulating the amount of tobacco forwarded by said drum, worm gearing driving said drum and said regulating means, picking mechanism acting on tobacco forwarded by said drum, and means independent of said gearing for driving said mechanism.

2. In a cigarette machine feed, the combination with a feed drum, of means for regulating the amount of tobacco forwarded by said drum, worm gearing driving said drum and said regulating means, picking mechanism acting on tobacco forwarded by said drum, means independent of said gear-

ing for driving said mechanism, and a winnowing device operating to deliver winnowed tobacco under said drum.

3. In a cigarette machine feed, the combination with a feed drum, of means for regulating the amount of tobacco forwarded by said drum, worm gearing driving said drum and said regulating means, picking mechanism acting on tobacco forwarded by said drum, and means independent of said gearing for driving said mechanism, said regulating means including means for pressing a mass of tobacco against said drum, and means for sweeping excess tobacco off said drum.

4. In a cigarette machine feed, the combination with a feed drum, of means for regulating the amount of tobacco forwarded by said drum, worm gearing driving said drum and said regulating means, picking mechanism acting on tobacco forwarded by said drum, and means independent of said gearing for driving said mechanism, said gearing including a constantly rotating shaft, worms on said shaft, and worm wheels driven by said worms and driving said drum and said regulating means.

5. In a cigarette machine feed, the combination with a feed drum, of means for regulating the amount of tobacco forwarded by said drum, worm gearing driving said drum and said regulating means, picking mechanism acting on tobacco forwarded by said drum, and means independent of said gearing for driving said mechanism, said picking mechanism including a picker roll coacting with said drum, and a re-picker acting on the tobacco after it is picked from said drum.

40 6. In a cigarette machine feed, the combination with a feed drum, of means for regulating the amount of tobacco forwarded by said drum, worm gearing driving said drum and said regulating means, picking mechanism acting on tobacco forwarded by said drum, and means independent of said gearing for driving said mechanism, said independent driving means including an electric motor and connections whereby said 45 motor drives said picker mechanism.

55 7. In a cigarette machine feed, the combination with a feed drum, of means for regulating the amount of tobacco forwarded by said drum, worm gearing driving said drum and said regulating means, picking mechanism acting on tobacco forwarded by said drum, means independent of said gearing for driving said mechanism, and a winnowing device operating to deliver winnowed tobacco under said drum, said picker mechanism including a picker roll coacting with said drum, and a re-picker acting on the tobacco after it has been winnowed.

60 8. In a cigarette machine feed, the combination with a feed drum, of a picker roll

coacting with said drum, and a winnowing device receiving tobacco from said roll and delivering winnowed tobacco under said drum.

9. In a cigarette machine feed, the combination with a feed drum, of a picker roll coacting with the side of said drum, a winnowing device receiving tobacco from said roll, and a re-picker under said drum and receiving winnowed tobacco from said device.

70 10. In a cigarette machine feed, the combination with a wall, of means for throwing tobacco against said wall to cause its lighter parts to slide down said wall and to cause its heavier parts to rebound from said wall and thereby become separated from said lighter parts.

80 11. In a cigarette machine feed, the combination with a wall, of means for throwing tobacco against said wall to cause its lighter parts to slide down said wall and to cause its heavier parts to rebound from said wall and thereby become separated from said lighter parts, and means for collecting said 85 heavier parts.

90 12. In a cigarette machine feed, the combination with a wall, of means for throwing tobacco against said wall to cause its lighter parts to slide down said wall and to cause its heavier parts to rebound from said wall and thereby become separated from said lighter parts, means for collecting said 95 heavier parts, and means for removing the heavier parts from said collecting means.

100 13. In a cigarette machine feed, the combination with a wall, of means for throwing tobacco against said wall to cause its lighter parts to slide down said wall and to cause its heavier parts to rebound from said wall and thereby become separated from said lighter parts, and a feed chute below and receiving said lighter parts from said wall.

105 14. In a cigarette machine feed, the combination with a wall, of means for throwing tobacco against said wall to cause its lighter parts to slide down said wall and to cause its heavier parts to rebound from said wall and thereby become separated from said lighter parts, a feed chute below and receiving said lighter parts from said wall, and a re-picker operating in said chute.

110 15. In a cigarette machine feed, the combination with a wall, of means for throwing tobacco against said wall to cause its lighter parts to slide down said wall and to cause its heavier parts to rebound from said wall and thereby become separated from said lighter parts, and a trough parallel with said wall for collecting said heavier parts.

115 16. In a cigarette machine feed, the combination with a wall, of means for throwing tobacco against said wall to cause its lighter parts to slide down said wall and to cause its heavier parts to rebound from said wall
